Application December 14, 1950, Serial No. 200,861

15 Claims. (Cl. 172—126)

1

This invention relates to vibration generators such as are used for sonic and under water sound vibration, processing, vibration testing and other similar purposes where reciprocating forces are required.

As manufactured heretofore, such generators or shakers generally have comprised a core structure magnetized by a winding energized from a direct current supply so that a high flux concentration exists across an air gap in the structure. An armature coil is positioned within the air gap and energized from a source of alternating current thereby to impart a reciprocating movement to an attached armature assembly. To prevent other than a substantially axial movement of the armature assembly, it is usual to support the assembly by means of a spiral spring or a pair of flexures, the opposite ends of which are in either case rigidly attached to the armature assembly and core structure, respectively. The flexures are located upon the opposite sides of the core structure, one of the flexures being connected to the assembly adjacent the armature coil, the connection between the other flexure and the assembly being made to one end of a rod or rods which passes through a centrally located aperture in the core structure so that the opposite end of the rod attaches to the bottom of a test table or bed located adjacent the armature coil. This mounting arrangement for the armature assembly gives satisfactory results in small shakers, but in large high power units it has been found that when the table and column are made rigid enough to withstand the resulting bending moments, their mass becomes so great that the acceleration of the armature assembly is limited. Another disadvantage of this construction is that, to shield the auxiliary signal generator from the effects of the leakage of flux from the air gap, it is necessary to mount the generator at the end of the column upon the opposite side of the coil structure from the armature coil, in which position the generator measures the velocity of such column end rather than the velocity of the table adjacent the coil.

It is accordingly a principal object of this invention to provide a vibration generator having an armature assembly whose mass is greatly reduced and wherein the bending moments due to mounting are minimized. Further objects are to position both the test table and signal generator where they are shielded from the air gap leakage flux, to mount the moving element of the signal generator so that it measures the velocity of the test table directly, and to provide flexures

2

which are uniformly stressed and are not subjected to fatigue and which are attached to the armature structure in a novel manner.

- In a broad aspect the invention contemplates 5 a vibration generator comprising a core structure which is preferably essentially E-shaped with a cylindrical air gap wherein a high flux concentration is produced by means of a field coil energized from a direct current supply. The generator 10 armature assembly comprises a coil located in the air gap and a test table which is positioned upon the opposite end of the core structure where it is shielded from the leakage flux adjacent the air gap. The table and coil are interconnected 15 by a plurality of elongated connecting members or columns which extend through respective apertures in the core structure and which are preferably although not necessarily equally spaced about the periphery of the table.
- 20 In a more specific aspect the ends of the respective connecting members are provided with axially disposed slots for receiving a cylindrical member or barrel which acts as a spacer for maintaining the relative spaced positions of the connecting 25 members. The armature coil is secured either by clamping it in the slots beneath the barrel or by securing to the extending end of the barrel in a plurality of encircling straps.

The armature assembly is constrained to move 30 axially without substantial lateral movement, which would tend to bring it into contact with the adjacent core structure by means of a respective pair of flexures or leaf springs located adjacent either end of the core structure so that the 35 respective flexures extend between the structure and the armature assembly. Preferably the connections between the armature assembly and the respective flexures are made pivotal, the ends of the pair of flexures adjacent the air gap attaching to the end ring of the armature coil and the ends of the opposite pair of flexures attaching the assembly adjacent to the test table. The opposite ends of the respective flexures are rigidly 40 attached to bosses extending from the core structure so that each flexure acts as a cantilever. By 45 making the flexure thickness in the direction of the axial movement of the armature assembly small with respect to the width of the flexures in a direction transverse to such movement, and by 50 gradually decreasing the transverse width of each flexure from a maximum width adjacent the rigid connection to the core structure to a minimum with adjacent the pivotal connection to the armature assembly, it is possible substantially 55 uniformly to stress the respective flexures, thus

reducing their mass so as to minimize the reciprocating mass of the armature assembly.

In another specific aspect each pivotal connection comprises three springs or leaves of a flexible material. The opposite ends of the respective leaves are substantially rigidly attached to the armature assembly and correlated flexures. Two of the leaves of each connection are arranged in spaced relationship in a common plane and the third leaf interposed between the two leaves with its plane substantially normal to the plane thereof, whereby movement of the end of the flexure bends all three leaves conjointly so that the resultant action is essentially that of a pivotal connection.

Another feature of the invention is the possibility of positioning a generator of electrical signals upon the opposite side of the core structure from the air gap, thereby to shield the generator from the leakage flux and at the same time making it possible to connect the moving element of the generator directly to the test table so that the output signal is a function of the velocity of the test table itself rather than of some other element of the armature assembly which may have another mode of vibration.

These and other objects, aspects and features of the invention will be apparent from the following description of a specific embodiment of the invention which refers to drawings wherein:

Fig. 1 is a plan view of a vibration generator;

Fig. 2 is a side elevation of the generator shown in Fig. 1;

Fig. 3 is a sectional view on lines 3—3 of Fig. 1;

Fig. 4 is an enlarged fragmentary elevation view showing the details of construction of one column of the armature assembly;

Fig. 5 is a fragmentary sectional view on lines 5—5 of Fig. 4;

Fig. 6 is a sectional view similar to Fig. 5 illustrating an alternative construction;

Fig. 6a is a fragmentary detail view of the end of the column in Fig. 6;

Fig. 7 is an isometric view of one of the flexures located at the coil end of the armature assembly;

Fig. 8 is a side elevation view showing the action of the flexure illustrated in Fig. 7; and

Fig. 9 is a fragmentary view of one of the flexures located at the table end of the armature assembly.

As is shown in Figs. 1 and 3, the vibration generator, chosen for purposes of illustration, comprises a substantially cylindrical core structure 10 of a low reluctance magnetic material. The core structure 10 is supported upon a base 12 having two integral upright brackets 14 which are located upon opposite sides of the base. At the top of each of the brackets 14 is provided a bearing surface wherein is journaled, respectively, one of the two oppositely disposed trunnions 16 which extend radially from the wall of the core structure 10. The trunnions 16 are maintained in contact with the bracket bearing surfaces by means of caps 18 which are bolted or otherwise secured to the respective brackets 16.

As is best shown in Fig. 3, the core structure 10 is provided with a deep annular recess 20 which is coaxially positioned with respect to the axis of the structure so that the core is separated into a central pole portion 22 and an outer ring portion 24. A core magnetizing coil 26 of conventional design is supported in the recess 20 by means of a plurality of spacers 28 and an annular cover plate 30 which is secured to the bottom surface of the ring portion 24 of the core

structure 10 by means of cap screws 32. With the cover plate 30 secured in place as described above, a magnetic path is completed which is essentially E-shaped in cross-section, thereby to form a cylindrical air gap 35 between the opposed cylindrical face of the extended end of the central pole portion 22 and the wall of the central aperture in the annular cover plate.

The armature assembly is designated generally by the numeral 40 and comprises a test table or bed 42 whereupon can be mounted test specimens or from which subsidiary mechanism or apparatus (not shown) can be driven. The table 42 is generally hexagonal in shape, as is shown in Fig. 1, and is provided with a skirt 44 (Fig. 1) at each of whose intersecting sides is provided a respective recessed boss 46 so that a rigid structure is formed with a minimum mass. As is best shown in Fig. 5, each of the bosses 46 is recessed from the bottom to provide a socket wherein is inserted the end of a respective hollow connecting member or column 48. The end of each of the columns 48, which is inserted in a respective boss aperture, is closed as at 49 except for a threaded hole for engaging a cap screw 50 which secures the column to the table 42. The top of the bosses 46 are also recessed so that the heads of the cap screws 50 are sunk well below the surface of the table 42, the recesses being threaded to provide a convenient means for attaching test specimens to the table.

The lower ends of the respective columns 48 are provided with axially extending slots having an offset in the bottom thereof wherein is inserted a cylindrical member or barrel 52 which acts as a spacer to maintain the columns in parallel relationship. The upper end of the barrel 52 is secured to each of the columns 48 by means of a flat-headed rivet 54 which also passes through internal spacers 56 and 58 positioned on either side of the barrel 52 within the column 48. It will be noted that, because of the offset of the lower portion of the slot, the spacers 56 and 58 are of different maximum thickness. The lower end of the barrel 52 is secured in a similar manner, but the spacer 60 is thinner than the corresponding upper spacer 56 so that a ring 62 can be inserted between the spacer 60 and the barrel 52.

The ring 62 is of a non-metallic material and has a lower portion which is of a greater width so that it is substantially of the same width as the slot to form an integral lip which acts as an end ring for an armature coil 65. The coil 65 is not carried upon a spool but is wound upon a collapsible mandrel (not shown) of wire having sufficient diameter whereby it is stiff enough so that the coil is self-supporting. The coil 65 is maintained in the wider portions of the slots in the columns 48 by means of a plurality of set screws 66. Each of the screws 66 is threaded, respectively, into the bottom of a correlated cylindrical block 69 which is held in the lower end of the corresponding column 48 by two opposed pins 68. The ends of the set screws 66 bear against the bottom of a lower end ring 70, thereby to compress the coil 65 between the lower ring 70 and the wider end of the upper end ring 62.

An alternative manner of securing the armature coil 65 is shown in Fig. 6 wherein the columns 48a are foreshortened and the slots for the barrel 52a have no offset but are positioned so that the barrel passes through the axis of the columns. The upper end of the barrel 52a

is secured to each of the columns by a respective rivet 54 and spacers 56a and 58a in a manner similar to that described in detail heretofore in connection with the embodiment shown in Fig. 5. The lower foreshortened end of the column 48a is necked down as at 49 and a rivet 54a passes therethrough to secure the lower end of the barrel 52a. The rivet 54a also passes through the separated portions of a slotted end ring 62a for the coil 65. The lower end ring 70 is supported by a plurality of straps 72 which extend downwardly beyond the ends of the respective columns 48a. Each of the straps 72 is bent around the lower end ring 70 so that its ends are adjacent either side of the slotted upper end ring 62a to which the strap ends are secured by two rivets 54b. These rivets also pass through the lower end of the barrel 52a which is inserted in the slot in the upper end ring 62a. The coil 65 is compressed between the end rings 62a and 70a by means of the set screws 66a (Fig. 6a), one of which is threaded into either side of a respective block 68a carried in the bottom of each strap 72.

The armature assembly 40 is mounted in the core structure 10 by removing the table 42 and inserting the columns 48 (or 48a) through equally spaced apertures 74 and 76 provided in the core structure 22 and the cover plate 30, respectively, so as to connect with the recess 20 in the core structure 10.

The armature assembly 40 is constrained so that it can move only in an axial direction by means of two pairs of deflectable members or flexures 80 located, respectively, at either end thereof. As is shown in Fig. 7, one end of each flexure 80 is rigidly attached by means of bolts 84 to a respective boss 82 which extends from the core structure. The two bottom flexures 80 are electrically insulated from the bosses 82 by means of spacers 87 of a non-conducting material which are positioned on either side of the flexures.

The opposite ends of the bottom flexures 80 are attached to the plastic lower coil end ring 70 by means of a pivotal joint 85, which is shown in Figs. 7 and 8 and will be described in detail hereinafter. As the bottom flexures are insulated from both the core structure 10 and metal portions of the armature assembly 40, the flexures can be used as electrical conductors for energizing the coil 65, thus eliminating loose wires and the resulting breakage. The upper flexures 80 are attached by similar pivotal joints 85a to arms 86 (Fig. 9) which extend respectively from two opposed columns 48.

As is shown in Figs. 7 and 8, each of the pivotal joints 85 comprises two spaced spring leaves 88, one end of each of which is rigidly clamped between a rectangular washer 89 at the end of the flexure by means of a screw 90. The opposite ends of the leaves are rigidly clamped in a similar manner to the top of a T-shaped bracket 91 whose other end is slotted to receive the coil end ring 70 to which it is secured by a screw 92. Interposed between the spaced leaves 88, and normally disposed at right angles thereto, is a third leaf 93 whose ends are rigidly clamped, respectively, by rectangular washers 94 and screws 95 to the side of the T-shaped bracket 91 and a block 96 mounted at the end of the outer side of the flexure. The pivotal joint 85a is generally similar in construction to the joint 85 described above, with the exception that the ends of the leaves opposed to

the ends clamped to the flexures are clamped to the arm 86 rather than the T-shaped bracket 91.

The operation of the above-described pivotal joints can best be understood by reference to Fig. 8 wherein the solid lines represent the normal unstressed position of the flexure 80. As the end ring 70 is moved upwardly to the position 70' indicated by the broken lines, the flexure is bent as is indicated at 80', the leaves 88 and 94 bending simultaneously at the line of intersection of their planes, which line is the equivalent of a pivot which moves without friction except for the internal bending strains in the leaves. From the above it will be apparent that with one end of each of the flexures 80 rigidly secured and the opposite end each having a pivotal connection, the respective flexures each act as a cantilever beam. To reduce the stress concentration at the rigid support, each of the flexures is tapered in width towards its pivoted ends at a rate which reduces the width of the flexure so that the stress therein is substantially constant throughout its length. With a uniform stress, the mass of the flexure can be minimized, thereby further reducing the total reciprocating mass of the armature assembly 40 to permit maximum accelerations.

The velocity of the table 42 of armature assembly 40 is determined by means of the output signal obtained from an armature coil 99 of a signal generator 100. The coil 99 is attached to the head at the lower end of a bracket 102. The other end of the bracket 102 is secured by means of a cap screw 104 in a socket located at the center of the table 42 so that the coil is disposed in the air gap of a generator stator. The stator comprises a portion 106 of a low reluctance material which is held in a recess in the end of the central portion 22 of the core structure 10 by means of a screw 108 which also passes through the end and spool pieces 110 and 112 comprising the remainder of the magnetic path of the stator. The spool piece 112 is a permanent magnet producing a constant magnetic flux in the air gap so that as the coil 99 is moved by the armature assembly 40, a voltage is induced in the coil which is a function of the velocity of the coil 99 and therefore of the table 42 to which it is attached.

The above-described vibration generator is energized by supplying a direct current to the field coil 26. When an alternating current is supplied to the armature coil 65, the armature assembly 40 is caused to reciprocate at a frequency determined by the frequency of the alternating current so that controlling the frequency of the coil current controls the reciprocating rate of the test table 42.

It should be understood that the present disclosure is for the purpose of illustration only and that this invention includes all modifications and equivalents which fall within the scope of the appended claims.

We claim:

1. A vibration generator comprising a core structure having an air gap, coil means for magnetizing the core structure to introduce a high flux concentration across said gap, an armature assembly carrying a table at one end thereof so that the table is positioned without said core structure upon the opposite side thereof from said gap, said assembly also including an electrical coil located in said air gap and a plurality of spaced elongated connecting members disposed about the periphery of said table and extending

through said core structure to support said coil, and flexure means extending between said structure and said assembly for limiting the travel of said assembly so that the coil is constrained to move axially without lateral contact with the core structure.

2. A vibration generator comprising a cylindrical core structure having an axial cross-section which is essentially E-shaped forming a cylindrical air gap at one end thereof, said structure having a plurality of equally spaced apertures extending therethrough at equal distances from the structure axis, a field coil disposed about the central leg of the core structure for magnetizing the structure to introduce a high flux concentration across said gap, an armature assembly carrying a table at one end thereof so that the table is positioned without said core structure upon the opposite end thereof from said gap, said assembly also including an armature coil located in said air gap and a plurality of elongated connecting members disposed about the periphery of said table and extending through respective apertures in said core structure to support said armature coil, and flexure means extending between said structure and said assembly for limiting the travel of said assembly so that the coil is constrained to move axially without lateral contact with the core structure.

3. A vibration generator comprising a core structure having an air gap at one end thereof, said structure having a plurality of equally spaced apertures extending therethrough at equal distances from the structure axis; a field coil for magnetizing the core structure to introduce a high flux concentration across said gap; an armature assembly carrying a table at one end thereof so that the table is positioned without said core structure upon the opposite end thereof from said gap, said assembly also including an armature coil located in said air gap, a plurality of elongated connecting members disposed about the periphery of said table and extending through respective apertures in said core structure, a spacer attached to the opposite end of the connecting members to maintain the relative position of the members, and attaching means for securing the armature coil to the spacer; and flexure means extending between said structure and said assembly for limiting the travel of said assembly so that the coil is constrained to move axially without lateral contact with the core structure.

4. A vibration generator comprising a core structure having a cylindrical air gap at one end thereof, said structure having a plurality of equally spaced apertures extending therethrough at equal distances from the structure axis; a field coil for magnetizing the core structure to introduce a high flux concentration across said gap; an armature assembly carrying a table at one end thereof so that the table is positioned without said core structure upon the opposite end thereof from said gap, said assembly also including an armature coil located in said air gap and a plurality of elongated connecting members disposed about the periphery of said table and extending through respective apertures in said core structure, a cylindrical member attached to the extending ends of the connecting members to act as a spacer therefor to maintain the relative position of the connecting members, and a plurality of straps encircling the armature coil to secure the armature coil to the outwardly extending end of the cylindrical member; and two pairs of spaced flexures extending between said

structure and said assembly for limiting the travel of said assembly so that the coil is constrained to move axially without lateral contact with the core structure, one pair of flexures extending between the table and the core structure, the other pair of flexures extending between the external end of the coil and the core structure.

5. A vibration generator comprising a core structure having an air gap at one end thereof, said structure having a plurality of equally spaced apertures extending therethrough at equal distances from the structure axis; a field coil for magnetizing the core structure to introduce a high flux concentration across said gap; an armature assembly carrying a table at one end thereof so that the table is positioned without said core structure upon the opposite end thereof from said gap, said assembly also including an armature coil located in said air gap and a plurality of elongated connecting members disposed about the periphery of said table and extending through respective apertures in said core structure, the extending ends of the respective connecting members having axially disposed slots therein, a cylindrical member secured in the slots in the connecting members to act as a spacer therefor to maintain the relative position of the connecting members, and a plurality of straps encircling the armature coil to secure the armature coil to the outwardly extending end of the cylindrical member; and flexure means extending between said structure and said assembly for limiting the travel of said assembly so that the coil is constrained to move axially without lateral contact with the core structure.

6. A vibration generator comprising a core structure having an air gap at one end thereof, said structure having a plurality of equally spaced apertures extending therethrough at equal distances from the structure axis; a field coil for magnetizing the core structure to introduce a high flux concentration across said gap; an armature assembly carrying a table at one end thereof so that the table is positioned without said core structure upon the opposite end thereof from said gap, said assembly also including an armature coil located in said air gap and a plurality of elongated connecting members disposed about the periphery of said table and extending through respective apertures in said core structure, said extending ends of the respective connecting members having axially disposed slots, a cylindrical member secured in the bottom of the slots in the connecting members to act as a spacer therefor to maintain the relative position of the connecting members, the armature coil being secured in the slots over the cylindrical member; and flexure means extending between said structure and said assembly for limiting the travel of said assembly so that the coil is constrained to move axially without lateral contact with the core structure.

7. A vibration generator comprising a core structure having an air gap, coil means for magnetizing the core structure to introduce a high flux concentration across said gap, an armature assembly carrying a table at one end thereof so that the table is positioned without said core structure upon the opposite side thereof from said gap, said assembly also including an electrical coil located in said air gap and a plurality of elongated connecting members attached to said table and extending through said core structure to support said coil, and two pairs of spaced flex-

ures located, respectively, adjacent the opposite ends of the core structure and extending between said structure and said assembly for limiting the travel of said assembly so that the coil is constrained to move axially without lateral contact with the core structure.

8. A vibration generator comprising a core structure having an air gap at one end thereof, said structure having a plurality of equally spaced apertures extending therethrough at equal distances from the structure axis; a field coil for magnetizing the core structure to introduce a high flux concentration across said gap; an armature assembly carrying a table at one end thereof so that the table is positioned without said core structure upon the opposite end thereof from said gap, said assembly also including an armature coil located in said gap and a plurality of elongated connecting members disposed about the periphery of said table and extending through respective apertures in said core structure, a cylindrical member attached to the opposite end of the connecting members to act as a spacer therefor to maintain the relative position of the connecting members, and a plurality of straps encircling the armature coil to secure the armature coil to the outwardly extending end of the cylindrical member; and two pairs of flexures for limiting the travel of said assembly so that the coil is constrained to move axially without lateral contact with the core structure, one pair of flexures extending between the table and the core structure, the other pair of flexures extending between the external end of the coil and the core structure.

9. A vibration generator comprising a core structure having an air gap, coil means for magnetizing the core structure to introduce a high flux concentration across said gap, an armature assembly carrying a table at one end thereof so that the table is positioned without said core structure upon the opposite side thereof from said gap, said assembly also including an electrical coil located in said air gap and a plurality of elongated connecting members attached to said table and extending through said core structure to support said coil, and two pairs of flexures located, respectively, adjacent the opposite ends of the core structure and extending between said structure and said assembly for limiting the travel of said assembly so that the coil remains in said air gap, the respective connections between the core structure and each of the flexures being substantially rigid, the respective connections to the armature assembly being pivotally arranged so that the flexures act essentially as cantilevers.

10. A vibration generator according to claim 9 wherein the thickness of the flexure in the direction of movement of the armature assembly is relatively small with respect to its width in a transverse direction to said movement.

11. A vibration generator according to claim 10 wherein the transverse width of each flexure is gradually decreased from a maximum width adjacent the rigid connection at the core structure to a minimum width adjacent the pivotal connection at the armature assembly, the rate of taper being such that the stress in the flexure is substantially uniform.

12. A vibration generator comprising a core structure having an air gap, coil means for magnetizing the core structure to introduce a high flux concentration across said gap, an armature assembly carrying a table at one end thereof so

that the table is positioned without said core structure upon the opposite side thereof from said gap, said assembly also including an electrical coil located in said air gap and a plurality of elongated connecting members attached to said table and extending through said core structure to support said coil, and two pairs of flexures located, respectively, adjacent the opposite ends of the core structure and extending between said structure and said assembly for limiting the travel of said assembly so that the coil is constrained to move axially without lateral contact with the core structure, the respective connections between the core structure and each of the flexures being substantially rigid, the respective connections to the armature assembly being pivotally arranged so that the flexures act essentially as cantilevers, each pivotal connection including two leaves of flexible material, the opposite ends of which are substantially rigidly attached to the armature assembly and correlated flexure respectively, the planes of the leaves being disposed at approximately right angles.

13. A vibration generator comprising a core structure having an air gap, coil means for magnetizing the core structure to introduce a high flux concentration across said gap, an armature assembly carrying a table at one end thereof so that the table is positioned without said core structure upon the opposite side thereof from said gap, said assembly also including an electrical coil located in said air gap, and a plurality of elongated connecting members attached to said table and extending through said core structure to support said coil, and two pairs of flexures located, respectively, adjacent the opposite ends of the core structure and extending between said structure and said assembly for limiting the travel of said assembly so that the coil is constrained to move axially without lateral contact with the core structure, the respective connections between the core structure and each of the flexures being substantially rigid, the respective connections to the armature assembly being pivotally arranged so that the flexures act essentially as cantilevers, each pivotal connection including two spaced leaves of flexible material and a third leaf positioned between the first two leaves with its plane substantially normal to the plane thereof, the opposite ends of all three leaves of each connection being substantially rigidly attached to the armature assembly and correlated flexure, respectively.

14. A vibration generator comprising a core structure having an air gap, coil means for magnetizing the core structure to introduce a high flux concentration across said gap, an armature assembly carrying a table at one end thereof so that the table is positioned without said core structure upon the opposite side thereof from said gap, said assembly also including an electrical coil located in said air gap and a plurality of equally spaced elongated connecting members disposed about the periphery of said table and extending through said core structure to support said coil, a generator of electrical signals which are a function of the table velocity interposed between said table and said core structure where said generator is shielded by said structure from leakage flux from said gap, and flexure means extending between said structure and said assembly for limiting the travel of said assembly so that the coil is constrained to move axially without lateral contact with the core structure.

15. A vibration generator comprising a core

11

structure having an air gap, coil means for magnetizing the core structure to introduce a high flux concentration across said gap, an armature assembly carrying a table at one end thereof so that the table is positioned without said core structure upon the opposite side thereof from said gap, said assembly also including an electrical coil located in said air gap and a plurality of equally spaced elongated connecting members disposed about the periphery of said table and extending through said core structure to support said coil, a generator of electrical signals which are a function of the table velocity interposed between the core structure and table where the generator is shielded from the leakage flux from said gap, said generator including a magnetized core member having a gap and a coil member, one of said members being attached to said core structure and the other member being attached

5

10

to said table so that there is relative movement between the members as the armature assembly moves, and flexure means extending between said assembly for limiting the travel of said assembly so that the coil is constrained to move axially without lateral contact with the core structure.
